United States Patent Office

Des. 183,515

Patented Sept. 16, 1958

183,515

AUTOMOBILE

Walter E. Hacker, Aidlingen, Germany, assignor to Daimler-Benz Aktiengesellschaft, Stuttgart-Unterturkheim, Germany

Application October 25, 1954, Serial No. 32,804

Term of patent 14 years

(Cl. D14—3)

FIG. 1.

FIG. 2.

FIG. 3.

Figure 1 is a perspective view showing an automobile embodying my new design and showing the front and one side of the vehicle.

Figure 2 is a schematic partial cross sectional view along lines 2—2 of Figure 1, and

Figure 3 is a perspective view showing the rear and other side of the vehicle of Figure 1.

The dominant features of my design reside in the portions shown by means of solid lines in the drawings.

I claim:

The ornamental design for an automobile, substantially as shown and described.
